(57) **CLAIM**

The ornamental design for an electrode assembly for electrical stimulation, as shown and described.

DESCRIPTION

FIG. 1 is a front left perspective view of a first embodiment of an electrode assembly for electrical stimulation showing

my new design, the electrode assembly including at least two electrodes and at least one wire secured to and extending from at least two electrodes;

FIG. 2 is a top plan view thereof;

FIG. 3 is a bottom plan view thereof;

FIG. 4 is a right side view thereof;

FIG. 5 is a left side view thereof;

FIG. 6 is a rear elevation view thereof;

FIG. 7 is a front elevation view thereof;

FIG. 8 is a front left perspective view of a second embodiment of an electrode assembly for electrical stimulation showing my new design, the electrode assembly including at least three electrodes and at least one wire secured to and extending from at least three electrodes;

FIG. 9 is a top plan view of the second embodiment;

FIG. 10 is a bottom plan view of the second embodiment;

FIG. 11 is a right side view of the second embodiment;

FIG. 12 is a left side view of the second embodiment;

FIG. 13 is a rear elevation view of the second embodiment;

FIG. 14 is a front elevation view of the second embodiment;

FIG. 15 is a front left perspective view of a third embodiment of an electrode assembly for electrical stimulation showing my new design, the electrode assembly including at least four electrodes and at least one wire secured to and extending from at least four electrodes;

FIG. 16 is a top plan view of the third embodiment;

FIG. 17 is a bottom plan view of the third embodiment;

FIG. 18 is a right side view of the third embodiment;

FIG. 19 is a left side view of the third embodiment;

FIG. 20 is a rear elevation view of the third embodiment; and,

FIG. 21 is a front elevation view of the third embodiment. The broken lines shown in the drawings illustrate portions of the electrode assembly for electrical stimulation that form no part of the claimed design.

The wire is shown with a symbolic break in its length. The appearance of any portion of the wire between the break lines forms no part of the claimed design.
